DEODORANT VAPORIZER

William M. Crook, Houston, Tex.

Application May 22, 1950, Serial No. 10,091

Term of patent 3½ years

(Cl. D16—2)

To all whom it may concern:

Be it known that I, William M. Crook, a citizen of the United States of America residing at Houston in Harris County, Texas, have invented a new, original, and ornamental Design for a Deodorant Vaporizer, of which the following is a specification, reference being had to the accompanying drawing, forming a part hereof, wherein:

The bottom of the vaporizer is substantially plain.

What I claim is:

The ornamental design for a deodorant vaporizer, as shown and described.

WILLIAM M. CROOK.
